H. E. BLEIER

FOUNTAIN PEN

Filed Dec. 18, 1924

Herman E. Bleier,

INVENTOR

BY *Rex Frye*
ATTORNEY

UNITED STATES PATENT OFFICE.

HERMAN E. BLEIER, OF DETROIT, MICHIGAN.

FOUNTAIN PEN.

Application filed December 18, 1924. Serial No. 756,881.

To all whom it may concern:

Be it known that I, HERMAN E. BLEIER, a citizen of the United States, and resident of Detroit, in the county of Wayne and State of Michigan, have invented new and useful Improvements in Fountain Pens, of which the following is a specification.

This invention relates to fountain pens, and more particularly to the automatic filling mechanism thereof.

The principal object of my invention is the provision of a self-filling fountain pen that can be quickly filled without immersing the pen point in the ink-well or other supply of ink.

Another object of the invention is the arrangement of an apertured cap at the rear extremity of the pen so as to telescope within the main barrel, the cap being arranged to receive ink by gravity from the ink-well as long as the apertures therein are uncovered by the barrel and then to act as a trap for the ink when the apertures are so covered by the barrel.

A further object of the invention is the provision of means for automatically filling a fountain pen from the rear end thereof without relying upon suction or a vacuum.

Other objects and advantages will be apparent from the following description, wherein reference is made to the accompanying drawings illustrating a preferred embodiment of my invention and wherein similar reference numerals designate similar parts throughout the several views.

In the drawings:

Fig. 1 is a vertical longitudinal section through my improved fountain pen in position for filling.

Fig. 2 is a side elevation of the pen in position for writing.

Fig. 3 is a detail elevation of the tube connecting the apertured cap with the main ink reservoir.

Fig. 4 is a detail view showing the mounting of the main reservoir barrel spring against which the filling cap operates.

Fig. 5 is a view from the rear end of the parts shown in Fig. 4, and

Fig. 6 is a detail view showing the position assumed by the filling cap and associated parts during the filling action.

Referring now to the drawings, the numeral 5 designates the barrel of the pen in which is housed a coil spring 6 surrounding a main reservoir 7 for ink communicating

at the forward end with a feeding neck 8 whereby ink from the reservoir passes to the underside of the pen point 9. Since the particular feeding mechanism employed does not enter into the present invention, the neck 8 has been illustrated only in elevation, it being understood that any operative form of feeding mechanism may be employed for properly feeding the ink from the reservoir 7 when the pen is being used for writing.

The main reservoir 7 comprises an elongated cylinder 10 in which is secured a hollow tube 11 herein shown as having a peripheral aperture 12 adjacent its forward extremity and a centrally apertured block 13 at its rear extremity adapted to completely fill the extremity of the cylinder 10. To maintain the tube 11 centrally of the cylinder 10 I provide a pair of oppositely extending arms 14 at the forward extremity of the tube 11 and adapted to engage the inner periphery of the cylinder 10. A cap 15 is arranged over the cylinder 10 and within the main barrel 5 contacting at its forward extremity against the coil spring 6 (note Figs. 1 and 6). The periphery of the cap 15 is provided with a series of filling apertures 16 through which ink from an ink well 17 or other ink supply may flow into the cap 15 whenever the cap is immersed in the ink supply 17. The apertures 16 are so placed between the extremities of the cap 15 that the filling apertures 16 will be completely covered by the main barrel 5 when the cap is forced forwardly against the tension of the spring 6. This is the normal position of the cap while the pen is being used for writing. To insure the maintenance of this position of the cap 15 as long as desired I preferably provide a lug or pin 18 adjacent the rear extremity of the cap 15 and arrange a hook 19 on the rear extremity of the main barrel 5 to receive the lug 18 and hold the cap against rearward movement until it is desired to replenish the ink within the reservoir 7. When it is desired to fill my pen, the cap 15 is rotated to release the lug 18 from its engagement with the hook 19 on the barrel, whereupon the pressure of the coil spring 6 forces the cap 15 rearwardly until the filling apertures 16 therein are uncovered. The rear extremity of the pen is then dipped within the ink well 17 or other ink supply until the filling apertures 16 are below the surface of the ink in the ink supply 17. The ink thereupon flows by

gravity into the cap 15 filling the cap up to the level of the ink in the ink well. The main barrel 5 is then pushed downwardly to force the tube 11 toward the rear end of the cap and at the same time to bring the rear end of the main barrel over the filling apertures 16 in the cap. As soon as the filling apertures 16 are covered by the main barrel, ink can escape from the cap 15 only through the tube 11, and as the tube 11 is forced toward the bottom of the cap 15 the ink trapped in the cap is forced out of the aperture 12 in the tube into the main reservoir 7. The main barrel 5 is then raised to again uncover the apertures 16 to permit more ink to flow from the ink supply into the cap 15, and then the barrel is again forced downwardly to receive the transfer of the ink from the filling cap 15 into the main reservoir. Two or at the most three reciprocations of the barrel suffices to fill the reservoir 7. The rear end of the pen is then removed from the ink supply and all ink on the surface removed by wiping. The cap 15 is then pressed forwardly and partially rotated to bring the lug 18 into locking engagement with the hook 19. The pen is now in position for writing.

Since the block 13 is firmly secured within the cylinder 10 by cementing or the like, there is no possibility of leakage of the ink from the reservoir 7 as long as the cap 15 is held in the position shown in Fig. 2.

During the filling operation all air within the reservoir 7 is forced out through the usual feeding aperture in the neck 8 of the pen. This escape of air at the pen point serves to remove any obstructions that might have been lodged within the feeding aperture, and also prevents the bubbling of ink at the rear of the pen during the reciprocations hereinbefore described.

While it will be apparent that the illustrated embodiment of my invention herein disclosed is well calculated to adequately fulfill the objects and advantages primarily stated, it is to be understood that the invention is susceptible to variation, modification and change within the spirit and scope of the subjoined claims.

Having described my invention, I claim—

1. In a fountain pen, a barrel, a reservoir for ink mounted substantially centrally therein, a spring arranged between the reservoir and barrel, a cap slidable between the reservoir and barrel and contacting the

spring, the cap having a filling aperture intermediate its ends adapted to be covered by the barrel at certain positions of the cap, and a filling tube mounted in the reservoir and open at its rear extremity to receive ink contained in the cap. 60

2. In a fountain pen, a barrel, a reservoir for ink mounted substantially centrally therein, a spring arranged between the reservoir and barrel, a cap covering the rear end of the reservoir and slidable between the reservoir and barrel against the tension of the spring, the cap having a plurality of filling apertures intermediate its ends adapted to be closed by the barrel at certain positions of the cap, and a filling tube mounted in the reservoir to receive ink contained in the cap. 65 70

3. In a fountain pen, a barrel, a reservoir for ink mounted substantially centrally therein, a spring arranged between the reservoir and barrel, a slidable cap snugly fitting at its outer periphery within the barrel and contacting the spring, the cap having a plurality of filling apertures intermediate its ends adapted to be closed by the barrel at certain positions of the cap, and a filling tube mounted in the reservoir to receive ink contained in the cap. 75 80 85

4. In a fountain pen, a cylindrical reservoir for ink, a cap slidable over the rear end of the reservoir and having peripheral apertures therein, a centrally apertured block closing the rear extremity of the reservoir, a filling tube fixed in the aperture of said block and communicating with the cap, and a barrel surrounding the reservoir and adapted to cover the apertures in the cap at certain positions of the cap relatively to the reservoir. 90 95

5. In a fountain pen, a cylindrical reservoir for ink, a cap slidable over the rear end of the reservoir and having peripheral apertures therein, a centrally apertured block closing the rear extremity of the reservoir, a filling tube fixed in the aperture of said block and communicating with the cap, a barrel surrounding the reservoir and adapted to cover the apertures in the cap at certain positions of the cap relatively to the reservoir, and a lug and hook connection arranged to hold the cap with its peripheral apertures covered by the barrel. 100 105

In witness whereof I hereunto set my hand.

HERMAN E. BLEIER.
